UNITED STATES PATENT OFFICE.

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY.

ROLLER SKATE.

Application filed June 9, 1921. Serial No. 476,258.

To all whom it may concern:

Be it known that I, WILLIAM F. REACH, a citizen of the United States, and resident of Springfield, in the county of Hampden and State of Massachusetts, have invented certain new and useful Improvements in Roller Skates, of which the following is a specification.

It is an object of my invention to provide a roller skate of simple construction, economical of manufacture, easy to assemble and easy to adjust.

The invention consists in the features and combination and arrangement of parts hereinafter described and particularly pointed out in the appended claims.

In the accompanying drawings

Figure 1 is a side view of a roller skate frame embodying my invention.

Fig. 2 is a bottom plan view.

Fig. 3 is a longitudinal sectional view.

Fig. 4 is a view taken from the rear.

Fig. 5 is a detail sectional view on line 5-5 of Fig. 1 looking in the arrow direction.

Fig. 6 is a sectional view on line 6-6 of Fig. 7.

Fig. 7 is a sectional view of Fig. 6 on line 7-7.

Fig. 8 shows details.

In these drawings the toe plate is shown at 1, the heel plate at 2 and at 3 is shown a bar or slide member which connects these plates adjustably. Both of the plates 1 and 2 are formed with a flange 1', 2' extending downwardly at their edges this flange on the toe plate extending around the front and along both sides and that on the heel plate extends around its rear edge and along both sides. The rear edge of the toe plate and the front edge of the heel plate are not downwardly flanged. The slide 3 is of a width to fit between the terminals of the flanges on the toe and heel plates, and this slide itself is provided with edge flanges 3' extending

downwardly to stiffen the plate. This plate is guided in and held by the brackets 4 forming wheel standards which are secured, one to the toe plate, and the other to the heel plate, and which furnish the supports for

the bearings 5 for the journal pins of the rollers not shown. These brackets are of sheet metal, and are stamped up into form to provide shoulders at 4' between which and the toe or heel plate, as the case may be, the slide or extension bar 3 is mounted as

shown in Fig. 5. The brackets are fastened to the heel and toe plates by providing lugs 6 on the upper edges of the brackets' sides, which lugs pass through openings in the toe or heel plate and are suitably secured.

These lugs may project above the surface of the plate to provide for riveting.

For locking the connecting bar 3 to the heel and toe plates, a locking member or detent 7 is pivoted at 8 to the standards or brackets 4 and these members have upwardly extending portions 7' provided each with a lug 9 to enter any one of a series of openings 10 in the slide or connecting bar 3. This locking member is stamped up out of a single piece of metal and with its pivots or pintles 8 integral therewith, and these pintles bear in the sides of the brackets or standards 4. The toe and heel plates are provided with openings near their inner ends into which the lugs 9 project after they have passed through the openings in the connecting plate, as clearly shown in Fig. 3. The assembly is readily made.

The locking member has shoulders at 7* which bear on the under side of the slide and acts to clamp the slide firmly in place taking up any looseness that may exist. The locking member is held in its clamping or locking position by a clamp 11 consisting of a plate having pintles 11' journaled in the sides of the standards 4. This clamping member has a flat upper edge and when turned to clamping position it has a camming action along the lower flat face of the pivoted locking member 7 and forces it firmly up into place with the flat upper edge bearing fully on the face of the locking member in which position the clamping plate will maintain itself in position.

It now stands with its upper end slightly on an inclination to the vertical line passing through the pivot 11' so that it is in self locking position.

It is subjected to little strain as the stresses exerted upon the locking member 7 are horizontal or in other words in the direction of the length of the extension bar or plate.

The clamping member 11 is arrested in its clamping position, that is, when thrown slightly past center as above described by shoulders 11* on the plate coming against the edges of the sides of the standards or brackets.

There is one of these adjusting or locking means for both the heel and toe portions of the skate which secures them to the connecting bar 3.

- 5 The swinging bracket or hanger 12 in which the roller journal pin is mounted at 5 is stamped up with sides which embrace the inclined standards or brackets 4 at the open sides of the latter, and rubber blocks or 10 bumpers 13 are interposed between the cross portion 12' of this swinging hanger and the lower end plate or portion 4* of the standard or bracket 4.

This end plate 4* inclines inwardly and 15 upwardly from both side walls and therefore forms an angular seat or recess for the bumper, which is provided with an upper side of angular form to fit the angular socket or recess in the end of the standard.

- 20 This end portion besides having the inclined formation as just described is formed at its central part with a partly cylindrical recess 14 to afford a bearing for the swivel pin 15, which lies on the upper side of this 25 cross wall portion 4* and is seated in the partly cylindrical recess.

This pin therefore passes through the sides or ears 12 of the swivelled bracket and simply lies in the seat or recess formed in 30 the upper face of the cross wall portion of the bracket or standard 4. The swivel pin is headed at one end and at its other end it is fastened by a cotter pin.

- The bearing at 14 for the swivel pin is 35 formed by making a corrugation in the end or cross wall portion 4* of the bracket, and this provides what may be termed a rib and recess interlock between the end wall of the bracket and the bumper which will hold the 40 bumper securely in place. This effect is enhanced by the fact that the construction described provides a recess in which the bumper lies, and the inclined walls of this recess afford bearings for the bumper substantially perpendicular to the direction of 45 the swinging movement of the bumper bracket which of course tends to carry the bumper with it. It will be observed that the tendency of the stresses imposed upon 50 the rubber bumper by the swinging of the swivelled bracket is to compress the rubber and wedge it firmly down into the recess at the end of the standard. The corrugation takes care of any tendency to side slip on 55 the part of the bumper.

The front clamp is composed of two members 16 of curved form stamped out of sheet metal and passing through openings 17 in the depending flange of the toe plate. Each 60 of these clamping members has an upturned grip 18 and this is curved from front to rear with its convex side facing inwardly to grip the shoe sole. Both members are perforated at their front ends. They overlap here and a single stud 19 passes through

their registering openings and through a slot 20 in the toe plate.

The pin is headed at its upper end, to rest on the toe plate. The pin has a threaded opening receiving an adjusting screw 21 70 which passes through a plain opening in the flange of the toe plate. By turning the screw, the front clamps can be adjusted to set the grips in or out.

The curved form of the grips will provide 75 a proper bearing on its convex inner side against the sole of the shoe in all adjustments of the clamping plates and prevent sharp bearing edges being presented to the shoe.

80 By providing the adjustment for the toe clamps at the front of the skate, I may employ a head of considerable size for turning the screw and this may be in the form of a finger piece for convenient operation without a key or wrench. The screw is threaded only in one direction, and both clamping members hinge on the same stud. The downturned flange serves the purpose of strengthening the toe plate and also affording an opening or bearing for the screw, and further of forming a guide for the clamp.

85 Reverting to the mounting of the swivelled bracket the end portion 4* of the standard 4 serves not only as the support for the rubber bumper but also the bearing for the swivel pin. No bearing holes or ears having bearing holes are needed as a part of the standard's formation but simply the partly 90 cylindrical bearing socket.

95 Instead of forming openings extending clear through the connecting bar, I may employ a bar provided with sockets or corrugations which would give an equivalent engagement with the locking means, and when I refer to "openings" in the appended claims I do so in a generic sense to cover the openings shown or any suitable formation which will afford similar engagement 105 with the lock.

I claim:

1. In combination in a skate a sectional foot plate, a connecting member having a plurality of spaced apart openings and slideable on the lower face of the foot plate, locking means to engage in any one of the openings of the connecting member and movable to and from the same, and a clamping member for holding the locking means in place 115 and a frame part connected to the sectional plate and on which said locking means and clamping member are mounted.

2. In combination in a skate, a sectional foot plate, a connecting bar on the lower face of the foot plate provided with a series of spaced openings, a bracket projecting from the lower face of the foot plate; a locking member pivotally mounted on said bracket swinging vertically and having a 120

portion to engage the openings in the connecting member, and a pivoted clamping member for the locking member, substantially as described.

5. 3. In combination in a skate, a sectional foot plate, a connecting member having spaced openings and slidably mounted on the lower face of the foot plate, a locking member having a portion to enter the openings, means depending from the lower side of the foot plate by which said locking member is movably mounted and a second portion integral with the portion first mentioned to bear on the under side of the connecting member to clamp it against the foot plate when said first portion is seated in the opening, and a clamping member for the locking member, substantially as described.

4. In combination in a skate, a sectional foot plate, a connecting member having openings and slidably mounted on the lower face of the foot plate, a wheel standard below the foot plate, a locking member having a portion to enter the openings, and a portion to bear on the under side of the connecting member to clamp it against the foot plate, and a clamping member for the locking member, both of said locking and clamping members being pivotally mounted in the standard, the clamping member when set extending substantially at right angles to the locking member.

5. In combination in a skate, a sectional foot plate, a connecting member having openings and slidably mounted below the foot plate, a wheel standard below the foot plate, a locking member pivoted at one end to the standard and having an upwardly extending portion at its other end to engage any one of the openings in the connecting member and clamping member also pivoted to the standard and having its upper end disposed to press upwardly against the locking member intermediate of its ends, to hold the same in locking position.

6. In combination in a skate, a sectional foot plate, a connecting member having openings and slidably mounted below the foot plate, a wheel standard below the foot plate, a locking member pivoted at one end to the standard and having an upwardly extending portion at its other end to engage any one of the openings in the connecting member and clamping member also pivoted to the standard and having its upper end disposed to press upwardly against the locking member intermediate of its ends, to hold the same in locking position, said clamping member when set being positioned across the center line of stress to be thereby self locking in position.

7. In combination in a skate, a sectional foot plate, a standard fixed thereto on its under side, a connecting member slidably guided by and between walls of the standard

and having spaced apart openings and locking means mounted between the walls of the standard to engage the openings in the connecting member to hold the same adjustably in place, and clamping means pivotally mounted between the walls of the standard for holding the locking means in place.

8. In combination in a skate, a sectional foot plate, a standard or bracket connected with the under side thereof having two walls bent to form shoulders on their inner sides spaced from the foot plate, a connecting member slidably guided between the walls of the standard and resting on the said shoulders, and locking means for the connecting member mounted on the standard for detachably fixing it to the standard, substantially as described.

9. In combination in a skate, a sectional foot plate, a two walled standard mounted on the under side thereof, a connecting member slidably mounted between the walls of the standard, locking means to fix the connecting member to the standard, and clamping means also mounted between the sides of the standard to hold the locking means and having stop portions to come against the edges of the walls of the standard, substantially as described.

10. In combination, in a skate, a foot plate comprising a sole and heel sections, a two walled standard carried by the lower side of one section and extending at an inclination thereto, a connecting member connected to the other section and slidably guided between the walls of said standard, a locking means mounted between the walls of the standard adjacent the connecting member for locking said connecting member against movement, and an operating device for said locking means, said operating means being mounted between the walls of the standard and projecting beyond the inclined edges thereof.

11. In combination in a skate, a sectional foot plate, a substantially U-shaped standard having its side walls secured thereto at their upper ends, a roller bracket pivotally mounted at the lower portion of the standard, a connecting member slidably mounted between the walls of the standard, and clamping means for said member mounted between the walls of the U-shaped standard, substantially as described.

12. In combination in a roller skate, a foot plate, a standard secured thereto formed of two side walls with a lower end wall, said end wall having a bearing recess for a journal pin on its upper side, a roller bracket, a journal pin therefor resting in said bearing recess, and a rubber bumper interposed between the end wall of the standard and the roller bracket, substantially as described.

13. In combination in a roller skate, a foot plate, a standard composed of two side

walls and a lower end wall lying between and with its middle portion above the lower ends of the side walls to form a recess, a bumper lying in said recess, a bracket for a roller embracing the bumper and a pivot pin for said bracket, said end wall of the standard having a bearing for the said pin on its upper side, substantially as described.

14. In combination in a roller skate, a foot plate, a standard composed of two side walls and a lower end wall lying between and with its middle portion above the lower ends of the side walls to form a recess, a bumper lying in said recess, a bracket for a roller embracing the bumper and a pivot pin for said bracket, said end wall of the standard having a bearing for the said pin on its upper side, said bearing being provided by a corrugation in said end wall which corrugation provides a rib in the recess for the bumper which bumper is recessed to receive said rib, substantially as described.

15. In combination in a roller skate, a foot

plate, a standard on the lower side thereof having side walls and a lower end wall re-entrant in respect to the side walls and thereby providing inclined wall sections convergent towards the center line between the side walls of the standard, a bumper mounted in said recess and having an angular face to fit the same, and a bracket for a roller supported pivotally by the said end wall, substantially as described.

16. In combination in a skate, a toe plate, having a slot at its forward end extending longitudinally thereof, a vertically arranged pin passing through the slot, a pair of clamping members overlapping at their front ends and pivotally mounted coaxially on the pin, and a screw on the under side of the foot plate engaging said pin to adjust the same, said clamp having upturned curved grips presenting their convex inner sides to the sole of the shoe, substantially as described.

In testimony whereof, I affix my signature. 45
WILLIAM F. REACH.
